UNITED STATES PATENT OFFICE.

ERNST HUGENDUBEL, OF STUTTGART, GERMANY.

COMBINED UMBRELLA AND CANE.

SPECIFICATION forming part of Letters Patent No. 609,435, dated August 23, 1898.

Application filed May 26, 1897. Renewed June 17, 1898. Serial No. 683,762. (No model.)

To all whom it may concern:

Be it known that I, ERNST HUGENDUBEL, a subject of the King of Württemberg, residing at Stuttgart, Germany, have invented certain new and useful Improvements in a Combination Umbrella and Cane, of which the following is a specification.

This invention relates to a combined umbrella and walking-stick which is distinguished by elegance of shape and facility and rigidity in use.

The invention consists of a combined umbrella and cane having a case or sheath adapted to be detachably connected with the handle, a perforated disk carrying a depending flange forming a socket secured to the rod of the umbrella, perforations in the lower end of the handle, and a pin housed in said socket and adapted to pass through the perforation in the disk and into one of the perforations in the said handle.

The invention consists, further, of details of construction hereinafter set forth, and defined in the claim.

Referring to the drawings, Figure 1 is a vertical section of the upper part of a combined umbrella and cane embodying my invention; Fig. 2, a section through $\alpha\alpha$ of Fig. 1; and Fig. 3 is a view of the complete article on a reduced scale, the lower end of which is shown in section.

Similar letters refer to the same parts wherever they occur.

The stick b of the umbrella a is connected by a nut c with the handle, so as to be capable of turning around axially. In order to effect this, the handle is made in two parts d and d' . Attached to the stick b is a disk b' , which carries a depending flange forming a socket b^2 for the reception of the pin e . The pin e prevents the turning of the rod when used as an umbrella. This result is secured by providing the part d' of the handle end with a number of holes e' , into some one of which the pin e falls when the article is held upright for use as an umbrella. The pin e works freely in and out of the socket b^2 and through the disk b' , but never passes entirely through the disk. Surrounding part d' of the handle is a sleeve f , internally screw-threaded at its lower end f' , by means of which the sheath or case g of the umbrella can be connected with the handle. For this purpose the sheath or case g , which may be

made of leather or other suitable material, is provided at its upper end with a lining or bushing g' , the upper end of which is threaded to receive the threaded end of the sleeve f . The lower end of the sheath g is provided with a socket g^2 to receive the stop g^4 . The lining g' causes the umbrella to assume a thin elegant shape and holds it together compactly. The lining g' and the socket g^2 are covered with leather or the like to form the sheath g , so that after the sheath g is on and the sleeve f and bushing g' are screwed together the umbrella has the appearance of a smooth walking-stick.

When the article is to be used as an umbrella, the sleeve f and bushing g' are unscrewed or otherwise detached from one another, the point of the stick being held down, so that the pin e may fall out of the hole e' and not prevent the sleeve f from turning. The sheath or case g , together with the bushing g' and stop g^4 , fastened thereto, can then be slipped off and put into the user's pocket. When the umbrella is opened and held up for use, the pin e falls into one of the holes e' in the end of the part d' of the handle and prevents the umbrella turning on its axis.

The length of the rod b is so arranged that the pin b^3 comes in contact with the stop g^4 , thus providing the necessary rigidity when the article is used as a walking-stick. The sleeve f and bushing g' may be also joined by means of a bayonet-joint or other fastening.

Having thus described my invention, I claim as new and desire to secure by Letters Patent—

A combined umbrella and cane, consisting of a case or sheath of leather or other material and adapted to be attached to or detached from the handle, a handle provided with holes in its lower end, a perforated disk attached to the rod of the umbrella, a depending flange secured to said disk and provided with a socket, and a pin adapted to be housed in said socket and to connect the disk with the said handle to prevent the rotation of the rod, substantially as set forth.

In witness whereof I have hereunto signed my name in the presence of two subscribing witnesses.

ERNST HUGENDUBEL.
